UNITED STATES PATENT OFFICE.

WALTER GRIFFITHS, OF RIVERHEAD, NEW YORK.

STEAM-BOILER FURNACE.

Application filed January 5, 1923. Serial No. 610,885.

To all whom it may concern:

Be it known that I, WALTER GRIFFITHS, a citizen of the United States, residing at Riverhead, Suffolk County, and State of New York, have invented certain new and useful Improvements in Steam-Boiler Furnaces, of which the following is a specification.

This invention relates to steam boiler furnaces of the type in which preheated air is used to promote combustion, and some of the objects thereof are to provide a furnace arch which is adapted to expand and contract under the action of heat and cold without any bricks of the arch moving from their original position, as from excessive heat and cooling off of same, as in previous furnaces of this type; to save coal, and reduce to a minimum, if not entirely, the additional expense of labor in making repairs in the brick-work; and to reduce the expense of material to a minimum; to provide a boiler-setting which facilitates the burning of the gases generated so that no available energy is lost in the smokestack, inasmuch as all gases are properly mixed with the oxygen of the inrushing air and are substantially entirely consumed; and to so conduct the preheated air in its circulation through the boiler-setting as to prevent any cold air from entering the furnace or smoke flues, thereby increasing the efficiency of the fuel used and preserving the material which is used in the setting.

These being among the objects of the present invention, the same consists of certain features of construction and combinations of parts to be hereinafter described and then claimed with reference to the accompanying drawings illustrating one embodiment of the invention, and in which

Fig. 1 is a side elevation of the furnace, partly in section, and parts broken away, the outer brick wall being shown at several places, and the boiler being shown in dotted lines, also the partitions in the air spaces of the furnace arch, the lower part of the furnace being shown in section on the line I—I, Fig. 4;

Fig. 2 is a transverse section on the line II—II of Fig. 1 looking forward;

Fig. 3 is a horizontal section, parts being broken away, on the line III—III of Fig. 2 looking downwardly;

Fig. 4 is a horizontal section on the line IV—IV of Fig. 1, parts being broken away;

Fig. 5 is a front elevation of the lower part of the furnace;

Fig. 6 is a diagrammatic development of the furnace arch on a horizontal plane;

Fig. 7 is a section on the line XV—XV of Fig. 1;

Fig. 8 shows a modification of the air passages of the arch-supporting sections.

The general features of the furnace will be first described, and these are best shown in Figs. 1 to 4 inclusive. The foundation or base 21 of the furnace may be of concrete or other suitable construction and provided with clean-out pits, and upon said foundation is supported massive arch-supporting sections 22, 23 of the boiler-setting. These arch-supporting sections comprise two, at each side wall of the furnace, each of them made of one piece of fire-brick or the like to extend the entire length of the furnace, or it may be preferred to make them in a number of pieces and cemented together end to end.

Upon the arch-supporting sections 22, 23, the furnace arch 24 is supported, and the rear inner wall of the furnace may be constructed in a similar manner of similar fire-brick or the like. The outer walls 25 of the furnace may be constructed of fire-brick, or ordinary brick, at the sides and the back of the furnace, and between the outer walls 25 and the furnace arch 24 are placed ordinary brick cemented together forming intermediate walls 26. The furnace is furthermore provided with a front plate 27 of cast metal and a metallic top plate 28, these being provided with suitable openings for doors, damper handles, etc. Front plate 27 is provided with an opening which is adapt-

ed to be closed by fire-door 29, while below the fire-chamber there is an ash-pit 30, the two being separated by a suitable grate 31.

A front wall 32 of fire-brick is built up back of the front plate 27, and this wall is supported upon a fire-door arch 33 extending from side to side of the furnace and supported upon the side walls of the furnace arch 24, it being composed of suitable fire-proof material, as, for instance, ordinary fire-brick. Within the furnace arch 24 the tubular boiler 34 is set upon supporting ledges 35 of fire-proof material, said boiler

having customary tubes 36. The stack 37 and the steam line 38 may be of ordinary construction for respectively discharging products of combustion, and steam to be used. Details will now be described.

The furnace arch 24 is of special construction, and is built up from hollow fire-bricks, as shown more fully in Figs. 2 and 3. Each fire-brick is preferably constructed according to my co-pending application Serial No 659,953 and the furnace-arch walls according to my application Serial No. 659,952.

Before the courses of fire-bricks to form the furnace arch are finally laid, and at a time when their incorporation in the furnace arch may be readily facilitated, partition-members of fire-brick material to provide partitions 52, 53, are inserted into the air spaces 41 which are formed within the furnace arch by the hollows of each fire-brick which have connecting heat-radiating portions 42. These fire-brick partitions are preferably laid and cemented into the position best shown in Figs. 1 and 6, that is to say, some of them are so set as to extend upwardly, while others are set to extend longitudinally of the furnace arch, while the vertical lines of partitions are joined with horizontal lines of partitions at corners, as best shown in Fig. 1. During the construction of the furnace arch, partitions are built up therein so as to provide at each side of the arch, as shown in Fig. 6, a partition 52, which extends vertically of the arch, and longitudinally thereof substantially in L shape, the partitions 52 thus being located at opposite sides of the fire-chamber, as are also L-shaped partitions 53, each of which is of greater scope than the partition 52, that is, its vertical portion is spaced away from the partition 52 so as to be nearer the rear end of the furnace, while the longitudinal portion thereof is spaced away from the partition 52 so as to be located nearer to the crown of the furnace arch. Likewise, from similar partition-members of fire-brick, longitudinal partitions 54, 55 and 56 are laid in the crown of the arch. It will be understood that Fig. 6 is schematic, or rather, a development of the furnace arch in a horizontal plane in order to more lucidly depict the manner in which the said partitions are built in to the air spaces of the furnace arch. These partitions will be referred to in detail as to their function later on.

At the back of the furnace, and within the furnace arch 24, are arranged transverse rear arches 57, 58, the arch 57 being below the arch 58 for the purpose of leading the smoke and products of combustion directly through the boiler tubes 36, a space being provided in front of the boiler and over it for returning the smoke and products of combustion into the stack 37, which before

entering the stack are deflected and guided thereinto by the upper rear arch 58.

Referring to Fig. 5, it will be seen that the front plate 27 of the furnace is provided at each side of the fire-door 29 with air-inlet openings 59, 60, 61, 62, 63 and 64. The said air-inlets admit air for preheating in the furnace before it is fed to the fire to support combustion. Preferably, the air-inlets 59 to 64 are so arranged that there is a vertical row of two each, as 59, 60, at opposite sides of the fire-door, while beyond these are two vertical rows of inlets 61, 62, 63, 64.

Referring more particularly to Figs. 1, 2, 4 and 6, each of the arch-supporting sections 22, 23 is provided with longitudinal passages 65, 66, 67, 68, 69, 70, and these are so arranged in said sections that when the latter are set in position, said passages will register with the air-inlets 59 to 64 inclusive. Preferably, and to facilitate the molding and the assembling of the arch supporting sections, they are made in two pairs, with each section 22 having an open longitudinal channel in one face, and each section 23 with four open longitudinal channels in one face. When the lower parts of the boiler-setting are built, the sections 22, 23, at each side of the setting, will have the open sides of the channels closed; the channels 65 in sections 22 having their open sides closed by the walls of the sections 23, and the sections 23 having the open sides of their channels closed by the masonry at the outer sides of said sections 23. Forming the passages in this way, better enables the long sections 22, 23 to be made if desired in block-like form extending the full length of the furnace. The air passages 66, 67 lead to the transverse passages 71, 72 in the fire-door arch 33, so that these passages 71, 72 communicate with air-inlets 60, 61 at both sides of the furnace, while the transverse passages 71, 72 are provided with jet-orifices 73, which are directed rearwardly into the fire-chamber. It will be observed that the hot material of the arch-supporting sections and the furnace arch, together with the fact that the passages 66, 67, partially intersect the fire-chamber, will assist in pre-heating the air which is led into the fire-chamber through the jet-orifices 73. The rear face of the fire-door arch 33 is provided with a recess 74, in which are located the jet-orifices 73, so that these are protected from the fuel in the fire-chamber. The recess 74 provides an overhang above the jet-orifices, which deflects a spray of pre-heated air downwardly and away from the metal surface of the boiler, thus protecting the boiler against burning out.

At the back of the fire-chamber there is a fire-bridge 75 of fire-proof material, and it is provided with transverse passages 76, 77, from which lead jet-orifices 78, which are located beneath an overhang 79 of the fire-

bridge for the purpose of protecting the jet-orifices. The transverse passages 76, 77 in the fire-bridge connect with side passages 65 which lead from air-inlets 59 at both sides 5 of the furnace, as best shown in Figs. 2 and 4. It is of course obvious that the passages 65 are longer than the passages 66, 67, and that they will sufficiently preheat the air which issues in jets from the fire-bridge orifices 78 to further facilitate combustion, as 10 this preheated air will come in contact with the flames as they pass over the fire-bridge. The spray of preheated air from the fire-bridge will be deflected by the overhang 15 thereof away from the boiler, and as the flame will thus be somewhat lifted by the said spray, and as the spray from the jet-orifices of the fire-door arch will press down on the flame, the carbon particles of the 20 products of combustion being thus confined will be practically, if not fully consumed, while the very highly heated products of combustion will not be poorly mixed with the oxygen of the preheated air and tend to 25 burn out the boiler or any metal surfaces by contact therewith.

The function of the partitions within the furnace arch will now be described. This is best illustrated from Figs. 1 and 6. At each 30 side of the furnace arch transversely restricted compartments or longitudinal passages 80 are formed by the partitions 52, and to the compartments 80 lead the passages 68 in the arch-supporting sections 22, 23, at a 35 connection between them being located at a distance back of the passages which lead to the fire-door arch. These compartments 80 are located at each side of the fire-chamber. and the air therein will be preheated. At 40 the point of juncture between each passage 68 and the compartment 80, but within the lower rear corner of the compartment 80, there is arranged a perforated air-distributor 81, preferably formed of fire-brick, and 45 the function of this air-distributor 81 is to spray the air within the compartment 80 and to deflect it away from the rectangular corner of the partition 52. The partitions 53 at each side of the furnace arch, together 50 with the partitions 52, provide restricted air-compartments 82 which extend around the rear ends and tops of the smaller compartments 80. As these restricted compartments 82 extend nearer to the back of the furnace 55 than the compartments 80, their rear ends are connected with the air-inlet passages 69 in the arch-supporting sections 22, 23. These compartments 82 are provided with air-distributors 83 similar to distributors 81. Beyond 60 and above the air-compartments 82 there are two restricted air-compartments 84 which extend from the back of the furnace to the front thereof, and these extend back of and over the compartments 82, and they 65 are also provided with air-distributors 85 at

the points where they connect with the longest longitudinal passages 70 in the arch-supporting sections 22, 23. It will be observed that the perforated air-distributors 81, 83 and 85 are located between the rear or inner 70 ends of the inlet-passages 68, 69, 70 and the main compartments 80, 82, 84, and that they have a considerable superficial area as compared with the cross-section of the passages 68, 69, 70. These air-distributors define the 75 proportions of large preliminary heating compartments or throats which are joined directly with the relatively small passages 68, 69, 70. In these preliminary compartments or throats, there is a tendency for the 80 air to be entrained or held back and not pass as through constricted passages directly to the fire-door arch. Hence, the incoming heated air is somewhat held back in the preliminary compartments or throats for a time 85 sufficient to be more highly preheated by the very hot walls surrounding these compartments. Now, when the so preheated air presses through the scattered holes of the 90 air-distributors, it is broken up into fine sprays which are ejected into, and the preheated air diffused into, the large compartments 95 80, 82, 84, having a very high temperature, and is given an intense heat therein, so that, when it is ejected in a further spray 100 from the fire-door arch, the intensity of the heat of the air is not comparable with air preheated in the usual way. This action produces perfect combustion in that the 105 gases and the burning particles in the flame are not chilled as by air of much less temperature. This tendency to chill is all the greater in the case of those passages which allow of an over strong draft through the fire-chamber. Furthermore, the cool outside air which tends to get through the crevices of all masonry boiler settings is given a sufficient time to heat up within the considerable dimensions of the compartments 110 80, 82, 84, so that there is no tendency for the incoming preheated air to be chilled by any leakage of cool outer air. The forward ends of the four compartments 80 and 82 lead to downward passages 86 in the brickwork just below the front end of 115 the boiler and above the fire-proof arch, while downward passages 87 also lead through said brick-work from the forward ends of the two compartments 84. These 120 downward passages 86, 87 lead the preheated air through openings in a cover-plate 88 upon the fire-door arch into chambers 89, 90 in opposite ends of the said arch. These 125 chambers 89, 90 are placed in the arch 33 in a plane above the transverse passages 71, 72 in the arch, so that jet-orifices 91 from said chambers 89, 90 will be arranged in a series above the series of jet-orifices 73. Thus, preheated air will be discharged in jets in a 130 broad spray and in ample volume from the

series of orifices of the fire-door arch. It will be apparent from the foregoing description that the air which flows in the spaces of the furnace arch is so conducted, along 5 various paths, which return from different points throughout the entire length of the arch, as to take full advantage of the high preheating effect of the walls of the arch. This is so, particularly because of the broad 10 and high stretches of fire-brick surfaces which form the walls of the plurality of thin passages or compartments 80, 82, 84 located at both sides of the furnace arch, and also because of the heat radiating surfaces provided 15 by the multitudinous heat radiating elements 42 which extend across the said passages, and also because of other obvious considerations.

The lower rear arch 57 indicated in Fig. 20 1 is preferably composed of hollow fire-brick, while the upper rear arch 58 is also hollow to provide an air space, which, however, is provided with one or more air-inlet openings 92 in the back wall of the furnace, 25 and the air space of the arch 58 communicates, as indicated, with longitudinal passages 93, 94. (See Figs. 2 and 6.) These longitudinal passages 93, 94 are defined by the partitions 54, 55, 56 extending longitudinally of the crown of the furnace arch, and the intermediate partition 56 is intersected by the steam dome 95 of the boiler, the stack 37 and the steam line 38, so that 30 two currents of preheated air will pass on opposite sides of the partition 56. This preheated air is lead downwardly by passages 96, 97 through the openings in the cover-plate 88 into the chambers 89, 90 of the fire-door arch, so that preheated air is 35 not only conducted over the front end of the furnace from the fire-door arch, but from the rear end, so that all available heat throughout the length and breadth of the furnace arch is utilized for preheating the 40 air for supporting combustion. The preferred practice as to the two series of jet orifices 78, 91 in the fire-door arch is to incline them towards each other as indicated by dotted lines in Figs. 1 and 3. Thus, the 45 jets of the two series will converge at the rear of the fire-door arch and the two broad streams of preheated air will cross or intersect within the fire-chamber and mingle with each other, joining forces as it were 50 at the most desirable points within the fire-chamber.

Referring to Figs. 1 and 7, it will be seen that the stack 37 and steam line 38 are provided with special means for admitting air 55 for preheating. There is a guard-cap 98 of fire-proof material, the edge of which may be downturned, and it is preferably composed of fire-proof material. This guard-cap 98 is provided with an opening 60 99 to receive the steam line 38, after there

has first been placed upon the steam line a collar or sleeve 100, also of fire-proof material, which is preferably of greater diameter inside than the steam line, in order to provide an annular space, which is filled preferably with an asbestos lining 101. Directly below the cap 98, and within its overhanging rim, the collar 100 is provided with an annular series of apertures 102 to admit outer air to internal downward passages 103 in the collar, which passages conduct air preheated by the steam line to the two longitudinal passages 93, 94, Fig. 6 before referred to. A similar provision is constructed around the stack 37. The passages 107 in the outer wall-portion of the arch are provided with air-inlets 111 in the front plate 27, Fig. 5. These passages do not connect with the interior of the furnace but mutually connect at the back of the furnace and are intended to admit of a circulation of air which tends to cool the boiler setting.

It is obvious that this invention may be variously modified, as by omitting, adding or substituting parts, and that the invention is not limited except as expressed in the claims. For instance, Fig. 8 shows one modification in which sections 115, 116 at the bottom of the furnace arch are provided with two and four air-inlet passages, respectively. Next to the fire is a section 117 of fire-proof material to protect the sections 115, 116 against the direct heat from the fire. These sections 115, 116 may be composed of any suitable fire-proof material, such as diatomaceous (Kieselguhr) brick cut and channeled as required, or they may be made of cement, consisting of a binder and ground diatomaceous or infusorial material. This material may be used at other places in the furnace, as for the collar 100, cap 98, etc.

What I claim as new is:

1. In a steam-boiler furnace, a boiler-setting having passages for air for supporting combustion, said passages leading, from inlet openings located in the wall of the setting, through and within the setting, separately to and out of jet-orifices in the rear of both the fire-bridge and the fire-door arch, whereby the respective passages to the fire-bridge and said arch are independent, both the bridge and the said arch having rearwardly directed overhangs located over the jet-orifices and deflecting the preheated air away from the boiler, the boiler being above the said bridge and arch, and the overhang of the fire-bridge being below the over-hang of the fire-door arch.

2. In a steam-boiler furnace, a boiler-setting having passages for air for supporting combustion, said passages leading, from inlet openings in the front wall of the setting, through and within the setting, to

and out of the fire-door arch, the passages to the said arch constituting returns disposed as a whole along substantially the full length of the side walls of the boiler-setting, and the bends of the returns occurring one behind the other so as to be located at different distances from the front of the setting.

3. In a steam-boiler furnace, massive arch sections of fire-proof material at the bottom and at both sides of the boiler-setting, and which extend for substantially the full length of the boiler-setting, and whereby the furnace-arch is supported, and a fire-bridge and a fire-door arch each having jet-orifices, the side walls of the boiler-setting having longitudinal air passages, and said sections being provided with longitudinal air passages, the passages in the boiler-setting and the passages in the arch sections communicating at different distances along substantially the full length of the arch sections, and conducting preheated air to said orifices.

4. In a steam-boiler furnace, the furnace arch, arch sections of fire-proof material at the bottom and at both sides of the boiler-setting, said setting having fireproof walls provided with air-heating spaces extending for substantially the entire length thereof, partitions in said spaces dividing the same into separate upwardly and forwardly extending passages at opposite sides of the arch, the upwardly extending portions of which passages have inlets in the bottom of the arch located at different distances away from the front of the furnace, and a fire-door arch having jet-orifices to which said passages lead downwardly, and said arch sections having longitudinal air passages leading to said inlets, whereby preheated air to support combustion may be conducted in paths, each of which leads rearwardly, upwardly, forwardly, and then downwardly and to the jet-orifices.

5. In a steam-boiler furnace, the furnace arch, arch sections of fire-proof material at the bottom and at both sides of the boiler-setting, said setting having fireproof walls provided with air-heating spaces extending for substantially the entire length thereof, partitions in said spaces dividing the same into separate upwardly and forwardly extending passages at opposite sides of the arch, the upwardly extending portions of which passages have inlets in the bottom of the arch located at different distances away from the front of the furnace, and a fire-door arch having jet-orifices to which said passages lead downwardly, and said arch sections having longitudinal air passages leading to said inlets, whereby preheated air to support combustion may be conducted in paths, each of which leads rearwardly, upwardly, forwardly, and then

downwardly and to the jet-orifices, and a fire-bridge having jet-orifices, said arch sections also having longitudinal air-passages leading to the orifices in the fire-bridge.

6. In a steam-boiler furnace, a boiler-setting having a longitudinal air-passage in the crown of the furnace-arch, the arch being constructed of fire-brick having said air-passage within it, and the wall of the furnace having an air-inlet passage leading to the rear end of aforesaid passage, said passages containing numerous heat-radiating portions of fire-brick, said longitudinal passage in the crown of the arch being intersected longitudinally by the steam-line, smoke-stack and steam-dome, and a fire-door arch having a series of jet-orifices to which said longitudinal passage conducts preheated air, said series of orifices extending along the said fire-door arch to form a broad spray of preheated air.

7. In a steam-boiler furnace, massive arch sections of fire-proof material at the bottom and at both sides of the boiler-setting, and whereby the furnace-arch is supported, and a fire-bridge having jet-orifices, said sections being provided with longitudinal air-heating passages which conduct preheated air to said orifices, and the said sections being formed in pairs with channels open at corresponding sides of the sections and which form the passages in the built-in sections.

8. In a steam-boiler furnace, the furnace arch, arch sections of fire-proof material at the bottom and at both sides of the boiler-setting, said setting having fire-proof walls provided with air-heating spaces, rising substantially throughout their height, partitions in said spaces dividing the same into separate passages at opposite sides of the arch, which partitions are relatively thin as compared with the extreme height and breadth of each passage, and which passages have inlets in the bottom of the arch located in the highest and broadest portions thereof and at different distances from the front of the furnace, and the highest and broadest portions of which passages constitute preheating compartments at both sides of the boiler-setting, perforated air-distributors located in the rear corners of said compartments directly over the said inlets, and a fire-door arch having jet-orifices to which said passages lead, said arch sections having air passages leading to said inlets, whereby preheated air to support combustion may be conducted to said jet-orifices.

9. In a steam-boiler furnace, the furnace arch, having fire-proof side walls provided with air-heating spaces of substantial height, inlet-passages to said spaces, partitions in said spaces dividing the same into separate passages at opposite sides of the arch, and

- communicating in succession with said inlet-passages at different distances from the front of the furnace, perforated air-distributors located in said side passages adjacent their points of communication with said inlet-passages, and dividing said side passages into preliminary preheating compartments at said points of communication and into larger preheating compartments at the other sides of the air-distributors, and a fire-door arch having jet orifices to which said side passages lead.
10. The combination of a furnace having a heated outlet pipe, a sleeve of thick fire-proof material around the pipe and having, between its outer and inner surfaces, air-heating passages extending downwardly through the body of the sleeve and leading from the outer air around said pipe to points of discharge in the combustion chamber, and an insulating lining between the sleeve and pipe.
11. The combination of a furnace having a heated outlet pipe, a cap of fire-proof material around the pipe, a sleeve of thick
- fire-proof material around the pipe and upon which said cap is supported, having between its outer and inner surfaces, air-heating passages extending downwardly through the body of the sleeve and leading from underneath the cap from the outer air around said pipe to points of discharge in the combustion chamber and an insulating lining between the sleeve and pipe.
12. In a steam-boiler furnace a fire-door arch, and means for conducting air and pre-heating it as conducted to said arch, said arch having longitudinal air passages connected with said means for conducting air, and also having two series of jet-orifices extending rearwardly from the said air passages for supplying preheated air to the fire-chamber, the two series extending longitudinally of the arch and behind said longitudinal passages, one series above the other, and the two series inclined with respect to each other so as to converge within the fire-chamber to form intersecting sprays of highly preheated air behind said arch.

WALTER GRIFFITHS.
